CHOOSE-HINDS COMPANY, OF SYRACUSE, NEW YORK, A CORPORATION OF NEW
YORK.

INCANDESCENT-ELECTRIC-LAMP FIXTURE.

1,119,050.

Specification of Letters Patent.

Patented Dec. 1, 1914.

Application filed October 28, 1911. Serial No. 857,880.

To all whom it may concern:

Be it known that we, ELDA G. SMITH and JOHN J. DOSSELT, citizens of the United States, and residents of Syracuse, in the county of Onondaga and State of New York, have invented a certain new and useful Incandescent-Electric-Lamp Fixture, of which the following is a specification.

This invention has for its object the production of a fixture for supporting incandescent electric lamps arranged in the wall of a car or other structure, when not in use, and movable out of said wall to be brought into service; and it consists in the combinations and constructions hereinafter set forth and claimed.

In describing this invention reference is had to the accompanying drawings in which like characters designate corresponding parts in all the views.

Figures 1 and 2 are vertical sectional views of this fixture and contiguous portions of the wall supporting the same, the parts of the fixture being shown in their positions assumed when the lamp is out of service, in Fig. 1, and in their positions occupied when the lamp is in service, in Fig. 2. Fig. 3 is a fragmentary sectional view taken at a right angle to Fig. 1. Figs. 4 and 5 are plan views, partly in section, of parts seen in Figs. 1 and 2.

This fixture comprises, generally, a carriage supported by a wall having an opening therein, said carriage being provided with an incandescent electric lamp socket and being movable rectilinearly through the opening to carry the lamp from in rear of the face of the wall to the front thereof, operating means for moving the carriage through the opening, and power-transmitting connections between the operating means and the rectilinearly movable carriage. Said means is preferably a door for closing the opening in the wall when the lamp is not in use.

1 is the wall having an opening 2 therein.

3 is a carriage supported, as hereinafter described, by the wall 1 and provided with an incandescent electric lamp socket 4 in which is supported the lamp 5.

6 is the hinged door for normally closing the opening 2, the door being carried by a base plate 7 secured to the front face of the

wall 1 and having an opening 8 registering with the opening 2 of the wall 1. Said door 6 serves as a reflector for the lamp 5 when the door is open.

The carriage 3 is slidably supported, and in this embodiment of our invention, depends from suitable supporting means carried by an inclosing box or case 9 arranged in rear of the wall 1 and supported thereby, the case having flanges 10 at its front end which lap the outer face of the margin of the wall 1 around the opening 2 and which are interposed between the base plate 7 and the wall 1, the base plate being formed with suitable recesses for said flanges. Fastening means as screws 11 pass through the flanges 10 and into the wall 1. In the illustrated embodiment of our invention, the carriage 3 includes a top plate 12 formed with a slot 13 extending in a direction parallel to the movement of the carriage, and the supporting means for the carriage consists of a guide 14 secured to the upper wall of the box 9 as by screws 15, the guide 14 having laterally extending flanges 16 extending under, and slidably interlocking with, the margins of the plate 12 on opposite sides of the slot 13.

A reflector 17 for the lamp 5 depends from the carriage 3 in rear of the lamp, said reflector also serving as a closure for the opening 2, when the door 6 is in open position.

18 and 19 are the terminals of the electric circuit in which the lamp is connected when in service, these terminals being supported by a suitable block of insulation 20 carried by the upper wall of the case or box 9; and 21 and 22 are terminals movable with the carriage and connected respectively to the lamp socket terminals 23 and 24, the terminals 21 and 22 of the carriage having sliding contact with the terminals 18 and 19. As here shown the terminals 18 and 19 are provided with extensions 25 and 26 running along the under face of the block of insulation 20, and the terminals 21 and 22 of the carriage are resilient and slidably engage with such extensions during the movement of the carriage 3. When the door 6 is closed, as seen in Fig. 1, the terminals 21 and 22 are out of engagement with the terminals 18 and 19, and during the initial

part of the opening movement of the door 6, the terminals 21 and 22 contact with the extensions of the terminals 18 and 19.

The extensions 25 and 26 and the terminals 21 and 22 of the carriage are formed with yielding interlocking means arranged to come in engagement when the door 6 has been opened to its full extent, the extensions being formed with projections 27 which are received in the depressions 28 on the terminals 21 and 22 respectively. The yielding interlocking engagement of the terminals 21 and 22 and the terminal extensions 25 and 26 prevents the door 6 from being jarred closed by the vibrations or swaying of the car equipped with our fixture.

The door 6 is here shown as hinged at 29 to the base plate 1 at one side of the carriage 3, and as arranged with its axis parallel to the axis of the lamp 5, that is, in vertical position, and a spring 30 tends to start the door 6 in its opening movement. The door is normally held closed by a sprung locking bolt or latch 31 carried at the free end of a flat spring 32 which is fixed at 33 at its other end to the upper wall of the box 9, the bolt being movable through an opening 34 in said wall and into a depression 35 in the top plate 12 of the carriage 3. The bolt is withdrawn out of the depression 35 to permit the spring 30 to start the door in its opening movement, by a button 36 movable in a suitable guide 37 in the base plate, said button being provided with a cam 38 which works in a slot 39, Fig. 3, provided in a part 40 rising from the spring 30. Obviously when the button is pressed inwardly, the part 40 will be elevated, raising the spring 32 and withdrawing the bolt 31 out of the depression 35 and permitting the door 6 to be swung open by the spring 30 and to carry the depression 35 out of alignment with the opening 34; and when the door is closed and the carriage moved back by hand to its starting position, the depression 35 will be aligned with the opening 34, the bolt moved into its operative position by its spring, and the part 40 pulled downwardly, said part acting on the cam 38 and causing the button to return to its starting position.

The power-transmitting means between the door and the carriage whereby the movement of the door moves the carriage rectilinearly through the opening 2, comprises a toothed rack 41 provided on the carriage and a toothed segment 42 associated with the door. As here shown the rack is provided on the edge of the top plate 12, and the segment is arranged near the upper edge of the door and overlaps the top of the carriage.

In operation, upon the depressing of the button 36, the door will be swung outwardly by its spring 30 sufficiently to engage the

terminals 21 and 22 with the extensions 25 and 26 of the terminals 18 and 19 so that the lamp 5 is in the electric circuit. The door is then fully opened by hand, the terminals 21 and 22 during such opening movement wiping along the extensions 25 and 26 until the parts 27 and 28 interlock to hold the door from jarring closed.

What we claim is:

1. An incandescent electric lamp fixture comprising a base plate having an opening therein, a carriage provided with an incandescent electric lamp socket, the carriage being movable to carry the lamp through said opening, and means for moving the carriage through the opening, said means being connected to the base plate and to the carriage and being movable relatively to the carriage and the base plate, substantially as and for the purpose described.

2. An incandescent electric lamp fixture comprising a carriage provided with an incandescent electric lamp socket, means for supporting the carriage, hinged means for moving the carriage rectilinearly relatively to its supporting means, and power-transmitting connections between the hinged means and the carriage, substantially as and for the purpose specified.

3. The combination with a wall having an opening therein; of a carriage provided with an incandescent electric lamp socket, the carriage being movable rectilinearly through the opening, a hinged door for the opening, the carriage being unsupported by the door, and power-transmitting connections between the door and said carriage, substantially as and for the purpose described.

4. The combination with a wall having an opening therein; of a carriage slidably supported by the wall and movable rectilinearly through the opening, the carriage being provided with an incandescent electric lamp socket, a hinged door for the opening, and power-transmitting connections between the door and the carriage, substantially as and for the purpose specified.

5. The combination with a wall having an opening therein; of a carriage slidably supported by the wall and movable rectilinearly through the opening, the carriage being provided with an incandescent electric lamp socket arranged to support the lamp in vertical position, a hinged door for the opening, and power-transmitting connections between the door and the carriage, substantially as and for the purpose set forth.

6. The combination with a wall having an opening therein; of a fixed guide supported by the wall and arranged at an angle to the opening, a carriage movable along the guide and being provided with an incandescent electric lamp socket, a hinged door for the opening, and power-transmitting connec-

tions between the door and the carriage, substantially as and for the purpose described.

7. The combination with a wall having an opening therein; of a depending carriage movable rectilinearly through the opening, fixed means associated with the wall for supporting and guiding the carriage, a hinged door for the opening, and power-transmitting connections between the door and the carriage, substantially as and for the purpose specified.

8. The combination with a wall having an opening therein; of a carriage movable rectilinearly through the opening, the carriage comprising a top plate formed with a slot extending parallel to the direction of movement of the carriage, fixed guiding and supporting means carried by the wall, and extending into the slot and having flanges slidably interlocking with the lower faces of the margins of the plate on opposite sides of the slot, a hinged door for the opening, and power-transmitting connections between the door and the carriage, substantially as and for the purpose specified.

9. The combination with a wall having an opening therein; of a carriage slidably supported by the wall and movable rectilinearly through the opening, the carriage being provided with an incandescent electric lamp socket arranged to support an electric lamp in vertical position, a door hinged at one side of the opening and arranged with its axis parallel to the axis of the lamp, and power-transmitting connections between the door and the carriage, substantially as and for the purpose described.

10. The combination with a wall having an opening therein; of a carriage movable rectilinearly through the opening, and being provided with an incandescent electric lamp socket arranged to support an electric lamp in depending position, a door hinged at one side of the opening and arranged with its axis parallel to the axis of the lamp, and power-transmitting connections between the door and the carriage, substantially as and for the purpose specified.

11. The combination with a wall having an opening therein; of a carriage supported by the wall and movable relatively thereto rectilinearly through the opening, the carriage being provided with an incandescent electric lamp socket, a hinged door for the opening, and power-transmitting connections between the door and the carriage comprising intermeshing toothed parts associated respectively with the door and the carriage, substantially as and for the purpose set forth.

12. The combination with a wall having an opening therein; of a carriage slidably carried by the wall and movable rectilinearly through the opening, the carriage being provided with an incandescent electric lamp

socket, and also with a toothed rack, and a hinged door for the opening provided with a toothed segment intermeshing with the rack, substantially as and for the purpose described.

13. The combination with a wall having an opening therein; of a carriage slidably supported by the wall and movable rectilinearly through the opening, the carriage being provided with an incandescent electric lamp socket arranged to support an electric lamp in vertical position, a door hinged at one side of the opening and arranged with its axis parallel to the axis of the lamp, and power-transmitting connections between the door and the carriage comprising intermeshing toothed parts fixed respectively to the door and the carriage, substantially as and for the purpose specified.

14. The combination with a wall having an opening therein; of a carriage slidably supported by the wall and movable rectilinearly through the opening, the carriage being provided with an incandescent electric lamp socket arranged to support the lamp in vertical position, the carriage being also formed with a toothed rack on its upper side, and a door hinged at one side of the opening and arranged with its axis parallel to the axis of the lamp, the door being provided with a toothed segment near its upper edge overlapping the top of the carriage and intermeshing with the rack, substantially as and for the purpose set forth.

15. The combination with a wall having an opening therein; of a carriage movable rectilinearly through the opening and provided with an incandescent electric lamp socket arranged to support the lamp in vertical position, and the carriage comprising a top plate formed with a slot extending parallel to the direction of movement of the carriage, and also with a rack in one edge thereof, fixed guiding and supporting means carried by the wall and extending into the slot, said means having flanges slidably interlocking with the under faces of the margins of the plate on opposite sides of the slot, and a door hinged at one side of the opening and arranged with its axis parallel to the axis of the lamp, the door being provided with a toothed segment near its upper edge for intermeshing with the rack, substantially as and for the purpose described.

16. The combination with a wall having an opening therein, and terminals of an electric circuit fixed relatively to the wall; of a carriage movable through the opening and provided with an incandescent electric lamp socket and with terminals for contacting the first-mentioned terminals, the terminals of the carriage having sliding engagement with the first-mentioned terminals, and being normally out of engagement.

ment with the first-mentioned terminals and movable into engagement therewith during the initial part of the movement of the carriage to carry the lamp out of the opening, and means for moving the carriage through the opening, substantially as and for the purpose set forth.

17. The combination with a wall having an opening therein and terminals of an electric circuit fixed relatively to the wall; of a carriage movable through the opening and provided with an incandescent electric lamp socket and with terminals for contacting the first-mentioned terminals, the terminals of the carriage having sliding engagement with the first-mentioned terminals, and being normally out of engagement with the first-mentioned terminals and movable into engagement therewith during the initial part of the movement of the carriage to carry the lamp out of the opening, a latch for normally preventing the carriage from outward movement, a spring tending to move the carriage sufficiently to engage the terminals of the carriage with the first-mentioned terminals upon the release of the latch, and means for moving the carriage through the opening, substantially as and for the purpose described.

18. The combination with a wall having an opening therein and terminals of an electric circuit fixed relatively to the wall; of a carriage movable through the opening and provided with an incandescent electric lamp socket and with terminals for contacting with the first-mentioned terminals, the terminals of the carriage having sliding engagement with the first-mentioned terminals and being normally out of contact therewith and movable into engagement therewith during the initial part of the movement of the carriage to carry the lamp out of the socket, a hinged door for the opening, and power-transmitting connections between the door and the carriage, substantially as and for the purpose specified.

19. The combination with a wall having an opening therein, and terminals of an

electric circuit fixed relatively to the wall; of a carriage movable through the opening and provided with an incandescent electric lamp socket and with terminals for contacting with the first-mentioned terminals, the terminals of the carriage having sliding engagement with the first-mentioned terminals and being normally out of contact therewith and movable into engagement therewith during the initial part of the movement of the carriage to carry the lamp out of the socket, a hinged door for the opening, power-transmitting connections between the door and the carriage, a latch for normally preventing the door from opening, and a spring tending to open the door to move the carriage sufficiently to engage the terminals thereof with the first-mentioned terminals upon the release of the latch, substantially as and for the purpose set forth.

20. The combination with a wall having an opening therein, and terminals of an electric circuit fixed relatively to the wall; of a carriage movable through the opening and provided with an incandescent electric lamp socket and with terminals for contacting with the first-mentioned terminals, the terminals of the carriage having sliding engagement with the first-mentioned terminals, and slidably engaged portions of the terminals having yieldingly engaging interlocking parts arranged to come into engagement when the carriage is moved to its position assumed when the lamp is in operative position, and means for moving the carriage through the opening, substantially as and for the purpose described.

In testimony whereof, we have hereunto signed our names in the presence of two attesting witnesses, at Syracuse, in the county of Onondaga, in the State of New York, this 8th day of September 1911.
